UNITED STATES PATENT OFFICE.

ALBERT G. SCHERER, OF CHICAGO, ILLINOIS, ASSIGNOR TO THE EXCELSIOR STEEL FURNACE COMPANY, OF CHICAGO, ILLINOIS, A CORPORATION OF ILLINOIS.

DESIGN FOR A REGISTER.

53,050.

Specification for Design.

Patented Mar. 4, 1919.

Application filed October 23, 1918. Serial No. 259,484. Term of patent 3½ years.

To all whom it may concern:

Be it known that I, ALBERT G. SCHERER, a citizen of the United States, residing at Chicago, in the county of Cook and State of Illinois, have invented a new, original, and ornamental Design for a Register, as shown in the accompanying drawing, which is a perspective view of my design.

What I claim is:—

The ornamental design for a register as shown.

In testimony whereof, I have hereunto set my hand and seal, at Chicago, Illinois, the first day of October, 1918.

ALBERT G. SCHERER. [L.S.]

Witnesses:

E. K. LUNDY, Jr.,
J. H. JOCHUM, Jr.
